Primary Examiner — Karen S Acker*Assistant Examiner* — Steven B Reinholdt, Jr.*(74) Attorney, Agent, or Firm* — Vorys, Sater, Seymour and Pease LLP; Scott M. Guttman(57) **CLAIM**

The ornamental design for a concrete vibrator cage, as shown and described.

DESCRIPTION

FIG. 1 is a perspective view of a concrete vibrator cage showing our new design;
FIG. 2 is a left side view thereof;
FIG. 3 is a right side view thereof;
FIG. 4 is a front view thereof;
FIG. 5 is a back view thereof;
FIG. 6 is a top view thereof; and,
FIG. 7 is a bottom view thereof.

The dashed lines used in FIGS. 1, 2, and 3 depict portions of the concrete vibrator cage that form no part of the claimed design. The broken lines shown in FIGS. 1 and 4-7 are environmental only and form no part of the claimed design. The dot-dash-dot broken lines depict the boundaries of the claim and portions of the concrete vibrator cage that form no part of the claimed design.

The interior surfaces adjacent to and opposite the beveled edge planes form no part of the claimed design.
